COMBINED FILLER AND ANVIL FOR TACK FASTENED BUTTONS

Filed Sept. 5, 1931

UNITED STATES PATENT OFFICE

GEORGE A. KING, OF WATERBURY, CONNECTICUT, ASSIGNOR TO SCOVILL MANUFACTURING COMPANY, OF WATERBURY, CONNECTICUT, A CORPORATION OF CONNECTICUT

COMBINED FILLER AND ANVIL FOR TACK-FASTENED BUTTONS

Application filed September 5, 1931. Serial No. 561,475.

This invention relates to tack-fastened buttons, and particularly to a combined filler and anvil for such buttons.

In tack-fastened buttons it is customary to make the part comprising the recessed back and hub of relatively heavy gage metal so that it will withstand the pressure applied to it in the operation of setting or attaching the button to an article, the recess in the back providing a space to receive an anvil of relatively heavy metal held in place in the back by a top or cap of thin metal which provides a finish for the button head.

By providing buttons with the combined filler and anvil contemplated by this invention, as hereinafter described, it is possible to make the button back and hub of much lighter gage metal than has heretofore been practicable.

20 The invention consists in a combined filler and anvil for tack-fastened buttons, comprising a blank so formed as to provide a filler having an anvil portion and arms offstanding therefrom, the filler and anvil portion 25 adopted to be arranged in the recessed back of a button and held in place relatively thereto by the button top or cap, and the arms so arranged as to extend into the button hub to provide means for guiding an attaching tack 30 into upsetting relation to the anvil and to hold the button fastened when the tack is upset or clinched, as will be hereinafter more fully explained and finally claimed.

In the accompanying drawings illustrating the invention, in the several figures of which like parts are similarly designated, Figure 1 is a side elevation of a finished button of the type for which the device of the invention is adapted. Fig. 2 is a top plan view, Fig. 3 is a side elevation, Fig. 4 is another side elevation, Fig. 5 is a vertical section and Fig. 6 is a bottom plan view of one form of combined filler and anvil contemplated by the invention, Figs. 3 and 4 looking 45 in the directions indicated by the arrows *a* and *b* of Fig. 2 and Fig. 5 being a section on line 5—5 of Fig. 2. Fig. 7 is an axial section of the complete button. Figs. 8, 9 and 10 show, in top plan, side elevation and bottom plan, respectively, a modified form of

the combined filler and anvil. Figs. 11, 12 and 13 show in top plan, end elevation and bottom plan, respectively, a further modification. Figs. 14 and 15 illustrate the manner in which the button is attached or fastened to an article or material by means of a tack.

55 The button proper comprises a recessed back 1, a hub 2, a top or cap 3 and the combined filler and anvil of the invention.

60 The combined filler and anvil as illustrated in Figs. 2 to 7, 14 and 15 comprises a blank, preferably circular in plan, slotted as indicated at 4 to provide three filler portions 5, of substantially sector shape, and three arms 6 offstanding substantially normal to the blank and having their free ends 7 formed or bent inwardly into close proximity for a purpose hereinafter appearing. The portion 8 of the blank lying intermediate the filler 70 portions 5 and arms 6 provides an anvil.

65 It will be noted, by reference to Figs. 7, 14 and 15, that the thickness of the blank and hence of the filler portions 5 and anvil portion 8 thereof is such as to snugly fit between the 75 back 1 and top 3 of the button, and that the arms 6 are of such a length and so formed as to closely fit within the hub 2. Thus when pressure is applied to the button, as is the case during the setting operation, neither the 80 back, top nor hub of the button will be injured, distorted or marred, but all will be supported and rigidly strengthened by the combined filler and anvil.

85 In attaching the button to an article or material, the button is placed upon one side of the material 9, see Fig. 14, and then a tack 10 is driven through the material and its point 11 passes through the hole 12 in the bottom of the hub 2 and is guided by the 90 portions 7 of the arms 6 into engagement with the anvil 8 against which it is upset or clinched, as shown in Fig. 15, substantially filling the space or chamber formed within the hub 2 by the arms 6, and bearing against 95 the anvil 8 and the inturned portions 7 of the arms 6. Thus the button is rigidly fastened upon the material.

100 The forms of the invention shown by the modifications illustrated in Figs. 8, 9 and 10

and 11, 12 and 13, respectively, differ in form but not in function from that just described.

In Figs. 8, 9 and 10 the device is shown as having four filler portions 5a and four arms 6a, and in Figs. 11, 12 and 13 it is shown as having two filler portions 5b and two arms 6b.

In all of the forms of the device illustrated it will be seen that the inturned free ends of the arms 6, 6a and 6b are so shaped and associated as to produce a definite opening for guiding the point of the tack and a well defined abutment against which the point of the tack, when upset or clinched, may bear.

As hereinbefore pointed out, it is apparent that, due to the fact that the combined filler and anvil takes the strain of the setting operation, it is possible to make the button back, hub and top much lighter gage stock

than has heretofore been practicable. Moreover, as distinguished from those buttons wherein a hub filler is used in addition to the anvil plate, the device of the invention simplifies the assembling operation in that it combines in a unitary element the part which provides a filler and anvil arranged between the back and top and the filler for the hub.

Therefore, by the employment of the device of the invention, not only are the structural parts of the button cheapened and simplified, but the assembly thereof is facilitated as well.

Various changes and modifications including and in addition to those shown and described are considered to be within the spirit of the invention and the scope of the following claims.

What I claim is:—

1. A combined filler and anvil for tack-fastened buttons, comprising in a unitary structure a filler member adapted for interposition between the back and top of a button and including an anvil portion, and arms offstanding from same and confined within the button hub, said arms providing guides for an attaching tack.

2. A combined filler and anvil for tack-fastened buttons, comprising in a unitary structure a filler member adapted for interposition between the back and top of a button and including an anvil portion, and arms partially severed from said filler member and offstanding from same and confined within the button hub, said arms providing guides for an attaching tack.

3. A combined filler and anvil for tack-fastened buttons, comprising in a unitary structure a filler member adapted for interposition between the back and top of a button and including an anvil portion, and arms partially severed from said filler member and offstanding from same and confined within the button hub, said arms having free ends bent into relatively close proximity and providing guides for an attaching tack.

4. A combined filler and anvil for tack-fastened buttons, comprising a unitary blank cut and formed to provide a filler adapted for interposition between the back and top of a button and having an anvil portion, and arms offstanding therefrom and providing means for guiding a tack into clinching relation to said anvil portion.

5. A combined filler and anvil for tack-fastened buttons, comprising a unitary blank cut and formed to provide a filler adapted for interposition between the back and top of a button and having an anvil portion, and arms offstanding therefrom and having free ends bent into relatively close proximity to 80 guide an attaching tack into setting relation to said anvil portion and to provide a stop for engagement with the upset portion of the tack to fasten the button.

6. A combined filler and anvil for tack-fastened buttons, comprising a unitary blank slotted to provide a plurality of arms and intermediate substantially sector-shaped filler members, said filler members adapted for interposition between the top and back of a 90 button, the center portion of said blank serving as an anvil, and said arms bent into off-standing relation to said blank to provide means for guiding a tack into upsetting relation to the anvil and for engaging the tack 95 when upset.

7. In a tack-fastened button having a back, a hub and a top, a combined filler and anvil having a filler portion arranged between the back and top and adapted to relatively support same, and arms offstanding from said filler portion and confined within said hub.

8. In a tack fastened button having a back, a hub and a top, a combined filler and anvil having a filler portion arranged between the back and top and adapted to relatively support same, and arms offstanding from said filler portion and confined within said hub, said arms having free ends bent to substantially conform to the shape of the bottom of said hub, said bent ends serving to guide an attaching tack into upsetting relation to said anvil and to engage the upset portion of said tack to fasten said button.

9. A combined filler and anvil for tack-fastened buttons, comprising in a unitary structure a filler member adapted to be arranged between the back and top of a button and provided with three offstanding arms serving as tack guides, the portion of the filler member lying between said arms serving as a tack anvil.

10. A combined filler and anvil for tack-fastened buttons, comprising a blank slotted to provide three substantially radially extending filler members adapted to be arranged between the back and top of a button, and three intermediate arms, said arms bent substantially normal to said blank and providing means for guiding an attaching tack,

and the portion of said blank lying intermediate said arms providing an anvil.

11. A combined filler and anvil for tack-fastened buttons, comprising a blank having 5 filler portions adapted for interposition between the back and top of a button, and a pair of oppositely disposed offstanding arms, the portion of said blank lying between said arms serving as an anvil, and said arms providing a guide for an attaching tack.

12. A combined filler and anvil for tack-fastened buttons, comprising a blank having 10 filler portions adapted for interposition between the back and top of a button, and a 15 pair of oppositely disposed offstanding arms, the portion of said blank lying between said arms serving as an anvil, and said arms formed to provide a guide for an attaching tack and to engage said tack when upset by 20 said anvil.

In testimony whereof I have hereunto set my hand this 4th day of Sept., A. D. 1931.

GEORGE A. KING.
